UNITED STATES PATENT OFFICE.

THOMAS RAYMOND ARDEN, OF BELLMORE, NEW YORK, ASSIGNOR TO JULIUS CHEIN, OF NEW YORK, N. Y.; ELIZABETH H. CHEIN EXECUTRIX OF SAID JULIUS CHEIN, DECEASED.

FIGURE WHEEL TOY.

Application filed July 20, 1924. Serial No. 729,059.

My invention relates to improvements in toys; an object of my invention is to provide a simple, attractive and useful toy which may be cheaply constructed. Another object of my invention is to provide a toy in which the parts are secured in position by a novel and simple means.

I accomplish these objects by the device illustrated in the accompanying drawings, 10 in which:

Figure 1 is a view of my device assembled, Figure 2 is a view of the horse, Figure 3 is a view of the platform, and Figure 4 is a view of the axle.

Similar characters of reference refer to similar parts throughout the several views.

The platform 1 consists of a plate of sheet iron provided with a plurality of slots 2, 3, 4, and 5. The rear slots 4 and 5 are 20 provided with enlarged apertures 4¹ and 5¹ respectively adjacent their forward ends.

Suitable railings 6, 7 may be provided, if desired, on the sides of the platform 1.

The horses 8 and 9 may be of any desired 25 pattern and are cut from blanks. They are of counterpart construction as to their lower operative parts, which include representations of hind legs 10 and of front legs 11. On the hind legs section 10, which are adapted 30 to be seated in the rear slots 4 and 5 respectively, I provide two cut out lugs 12, 13 to position the hind legs 10 in the slots as will be hereafter more particularly explained. On the front leg section 11 I 35 provide a seat 14 cut in the lower edge of the section 11 and a lip 15 adjacent the seat 14. The device is mounted on traction wheels 16, connected by an axle 20 provided with cranks 18, 19.

The horses are mounted on the platform 40 by inserting the lug 13 in the enlarged apertures 4¹, 5¹ respectively of rear slots 4 and 5 and then sliding them rearwardly with the lug 12 above the platform 1 and the lug 13 below the platform 1, thus forming 45 a sliding connection between the horse and the platform.

The front leg sections 11 are then inserted 50 in the forward slots 2 and 3 respectively and the cranks 18, 19 respectively of the axle 20 are engaged by the seats 14. The lip 15 is then bent over under the axle 20 and across the seat 14 and pinched thereon, thus securely but loosely holding the axle 20 in its 55 seat.

The device being thus assembled, the traction wheels will be rotated by pushing the device along the floor or other surface, thereby rotating the axle and its integral cranks. The cranks engaging the forward 60 leg sections of the horses will cause them to slide forward and backward and at the same time the forward ends of the horses will rise and fall giving the appearance of race horses in action.

Having thus described my invention, what I claim is:—

1. In a sheet material toy, a platform, a slot in said platform, a blank representing a figure and having an extension which 70 stands perpendicularly thru said slot, lugs bent from said extension, said lugs lying respectively above and below said platform to secure the blank and platform in sliding connection.

2. In a device of the character described, the combination of a platform, a slot in the platform and having an enlarged aperture, a member mounted on the platform and having a section extending through the platform, a lug on the said section adapted to pass through the said aperture and below the platform to position the member.

3. In a device of the character described, the combination of a platform, slots in the platform, a member mounted on the platform and having two sections extending through the platform, lugs on one of the said sections adapted to position the said member on the platform and to permit sliding action between the said member and the platform, a seat in the other of the said sections, an axle in the said seat and a lip integral with the member and adapted to be bent over to hold the axle in the seat.

4. In a device of the character described, the combination of an axle, traction wheels thereon, a platform, a member movably mounted on the platform and having a section extending through the platform, a seat in said member adapted to receive the axle and a lip adjacent the seat to be bent over parallel to said member to secure the axle in the said seat.

In testimony whereof, I have signed my 105 name to this specification this 24 day of June, 1924.

THOMAS RAYMOND ARDEN.
